UNITED STATES PATENT OFFICE.

LEWIS H. FALLEY, OF KANSAS CITY, MISSOURI, ASSIGNOR TO M. H. FALLEY, OF KANSAS CITY, MISSOURI.

DREDGING APPARATUS.

Application filed June 4, 1923. Serial No. 643,244.

To all whom it may concern:

Be it known that I, LEWIS H. FALLEY, a citizen of the United States, and resident of Kansas City, county of Jackson, State 5 of Missouri, have invented a certain new and useful Improvement in Dredging Apparatus, of which the following is a complete specification.

The present invention relates to dredging 10 apparatus, and aims to provide an improved construction of this character adapted for efficient operation in producing such shifting operation of the material forming the beds and banks of rivers or waterways as is required for excavating or deepening the 15 channels thereof, breaking up sand bars, protecting the banks of streams, or analogous operations.

Accordingly, I have devised a sluicing 20 dredge device adapted to be operated either in a stationary position, or in conjunction with a moving raft or boat, for exerting a combined digging and sluicing action upon the river bed or bank, and washing the material of the same out of the path of movement of the device. This operation is effected by a deflector blade structure so arranged as to produce not only a plurality of minor digging currents but also a set of 25 washing and carrying currents operating to both loosen up the material and then sluice or wash the same laterally to one side of the apparatus and out of the path of the main current flow.

It is also sought to produce a light, simple 30 and conveniently adjustable and portable apparatus adapted to be readily shifted into or out of operative position and transported from one point to another, and also 35 a construction adapted to be assembled in units of greater or less number, according to the scale of operation required.

With these general objects in view, the invention will now be described by reference 40 to the accompanying drawings illustrating certain forms of construction which I have devised for carrying the invention into practice, after which those features and combinations deemed to be novel and patentable 45 will be particularly set forth and claimed.

In the drawings—

Figure 1 is a plan view of the dredging 50 apparatus constructed in accordance with the present invention;

Figure 2 is a side view illustrating the

same in operative relation to the bed of a stream;

Figure 3 is an enlarged inverted plan view of one of the units of the dredging apparatus shown in the upper part of 60 Figure 1;

Figure 4 is a front elevation, partly broken away, of one of said units shown in the lower part of Figure 1;

Figure 5 is a section on the line V—V of 65 Figure 1, but on a larger scale;

Figure 6 is an enlarged sectional detail view, taken on the line VI—VI of Figure 2;

Figure 7 is a similar detail section taken 70 on the line VII—VII of Figure 1;

Figure 8 is a plan view showing a modification of the duplex form of the dredging unit and its relation to the hull of a boat;

Figure 9 is a side elevation of the same, 75 in operative relation to the bed of a stream; and

Figure 10 is a rear elevation of said modified form of dredging units.

Referring now to the drawings, in detail, and more particularly to Figures 1 to 5, these illustrate the improved type of dredging unit as comprising a framework 10 taking the general form of a right triangle having the sides thereof corresponding to the hypotenuse provided with a baffle structure designed to be presented obliquely with reference to the direction of the stream current. This baffle structure is composed of an upper 80 row of deflector blades 11 of curved and slightly twisted outline, and a lower row of deflector blades 12 of similar outline (see Figure 5). The exact size, pitch and contour of these blades are immaterial, as these characteristics would of course depend upon the particular conditions of use, but in the present instance, the blades of each group are designed to split up the main current into a multiplicity of minor, secondary currents directed downwardly toward the bed of the stream and also deflected outwardly or laterally away from the main line of the current flow. These blades are carried by the forward portion of a horizontal partition 14 which is bent downward at an angle 85 at its front margin 15, the lower blades 12 being carried by the underface of this angular margin, while the upper blades are supported on the top face of said marginal 90

100

105

110

portion, the front edge of the partition lying flush with the lower ends of the blades 11, as shown in Figure 5. This partition 14 serves to divide the current and thereby distribute the same to the two sets of deflector blades in an obvious manner. The middle portion of the partition 14 is provided with a set of openings 16 formed by striking up baffle blades 17 serving to assist in deflecting 10 a substantial part of the current to the underside of the partition, and also to facilitate the placing of the device into or removing it from operative position by relieving the pressure which would be incident to an 15 unbroken surface.

At the front and along the outer side of the device is provided a curved outer wall forming a hood member 20 extending in front of and partially over the baffle structure; this cooperates with a vertical wall 21 along the other side of the frame to impound the current received from the open rear end of the device and directed to the deflector elements or blades 11 and 12. The forward portion of this hood projects down flush with the lower ends of the deflector blades 11, which portion of the hood is provided with an inner wall 22 connected with the adjacent upper blades 11. This end of the hood is also provided with a depending nose portion 23 having fins 24 and projecting flush with the lower ends of the lower blades 12, for the purpose of protecting the same and also directing the currents from said 25 blades directly against the bed of the stream. The lower edge of the remaining or rear portion of the hood 20 is cut away opposite the lower end portions of the corresponding blades 11 to provide a discharge space 25 30 from said blades, said space being separated from the lower blades 12 by a horizontal fin 26 projecting outward flush with the lower edges of the blades 11.

The type of dredging unit above described 45 is made in rights and lefts, for use in pairs, as illustrated in Figure 1, where such a pair is shown connected with the prow of a raft 30 of the catamaran type. Each unit is equipped with parallel rearwardly and upwardly projecting arms 31 carrying pins or studs 32 for engagement in channel guides 33 provided at the outer sides of the hulls of the raft, and also between said hulls, the latter guides being supported by brackets 34 50 depending from the opposite sides of an opening 35 in the forward end of the deck 36 which bridges the space between the hulls (see Figures 1 and 7). The adjoining sides of each pair of dredging units are also provided with vertical guide ribs 37 adapted for sliding engagement with each other (see Figure 6), thereby allowing relative vertical play of said units but preventing any relative movement of the same forward and 55 backward, which is of advantage in case of

their meeting an obstruction which would thus be opposed by the combined action of both units. For each of the dredging units at the prow of the raft, the latter is provided with a winch device 38 operating cables 39 trained over guide pulleys 40 and connected with the rear ends of the arms 31, whereby the latter may be conveniently raised and lowered. A lifting cable 41 is also suitably connected to each dredging 70 unit for cooperation with the cables 39 in lifting the unit, and also for raising and lowering the same about the axis of the pins 32, each of said cables being carried around pulleys 42 mounted on a derrick 43 provided 75 with a winch 44.

The raft is provided with the usual centerboards or drop keels 46, adapted to be raised and lowered by means of winches 47, the members 46 serving as drags or anchors and to steady and hold the rear end of the raft in alignment by neutralizing the action of cross currents. The raft may also utilize propellers 48 operated by the usual power connections (not shown) for producing such 80 movement of the raft as is desired.

The described form of dredging unit, made in rights and lefts, enables the width of the apparatus to be extended to take care of more extensive operations or wider stream channels by simply expanding the width of the raft and attaching additional dredging units as illustrated in Figure 1. In such cases, additional shorter hulls 30, are connected, as indicated at 52, to the sides of the hulls 30, and to the prows of these auxiliary hulls 30' are attached additional dredging units in the same manner as already explained with reference to the main hulls 30, the shorter length of the hulls 30' permitting these additional dredging units to be positioned to the rear of the units attached to the main hulls. As illustrated, the hulls 30' carry derricks 43 and winch devices 38 and 44 for use in adjusting the position of the dredging units.

In the operation of the apparatus above described, the raft is moved slowly down stream with the baffle structures or dredging units in proximity to the bed of the stream, or against a sand bar, according to the nature of the work to be performed. The stream current thus intercepted by each baffle structure is received in the open rear side of the same and deflected by the horizontal partition 14 to the two sets of blades 11 and 12. Both sets of deflector blades operate to break up the main current into a corresponding number of minor secondary currents which are directed downward and outward, the principal function of the lower blades 12 being to discharge these minor currents forcefully against the material forming the bed of the stream, thereby loosening said material by a sluicing action 110

and washing it outward in a lateral direction with reference to the course of the main current. This sluicing or digging action is carried out with greatest effect at the 5 nose portion of the dredging unit where both the upper and lower blades 11 and 12 are caused to discharge the sluicing currents directly toward the stream bed, that is, through that space at the rear of the nose 10 portion 23 and between the fin 26 and the front corner of the dredging unit. The remaining upper blades 11 act principally to exert an outward carrying action, as the horizontal fin 26 modifies the movement of 15 the secondary currents discharged from the blades 11 so as to direct said currents to a level slightly higher than that of the lower or digging currents, with the result that the material being sluiced is washed outward 20 away from the apparatus farther than would otherwise be the case.

Referring to Figures 7 to 9, these views illustrate simply a modified construction of the duplex form of the dredging units, in 25 which a pair of right and left units are combined in one rigidly connected assembly open entirely across its rear end, and with no central partition between the baffle structures at the front or nose portion of the device. A single pair of arms 32' is used 30 to connect the assembly to the hull 30" of a boat, the connections and method of operation being otherwise substantially the same as with the forward dredging units of the preceding construction, excepting that a 35 single winch device 38 and derrick structure 43 are required for raising and lowering the apparatus.

It is thus apparent that I have devised 40 an efficient and yet comparative simple dredging construction for carrying out the desired objects of the invention, as regards either the excavating or deepening of river channels or straightening of the same, or 45 the breaking up and removal of a sand bar, or the like. As a secondary result, in the excavation of the beds of waterways, the material is moved away out of the path of the main current flow, and so deposited as 50 to build up the sides of the channel, thus protecting the banks from damage, such as that due to the action of cross currents. It is to be observed also that the apparatus 55 is of a light and easily manipulated character, by virtue of its being of sheet metal construction, and the means employed for readily adjusting the same as to elevation and angle of operation, by which means moreover the dredging units may be shifted 60 into and out of position on the deck of the boat or raft and transported from place to place as required. Again, while the operation of the device has been described as taking place with the boat or raft moving slowly 65 down stream, conditions may require its

use in a stationary position, as for protecting a bank or channel and the like, and it is therefore to be understood that the right is reserved to make all such changes or modifications as may fairly fall within the scope 70 of the appended claims.

What I claim is:

1. A dredging apparatus adapted to be submerged in the path of a water current and comprising a set of water-deflecting elements of downwardly curved outline adapted to produce a plurality of minor or secondary currents directed downward toward the bed of the waterway, and a second set of water-deflecting elements above said first set and of downwardly curved and twisted outline adapted to produce a plurality of auxiliary currents directed both downwardly and outwardly at a level slightly above the path of said first minor currents for augmenting the outward carrying effect of the latter. 75

2. A dredging apparatus adapted to be submerged in the path of a water current and comprising a plurality of deflector elements in position to intercept the current and of downwardly curved outline adapted to produce a plurality of minor currents directed downward toward the bed of the waterway, a plurality of deflector elements above said first elements, said latter elements being of downwardly curved and twisted outline to produce a plurality of auxiliary currents directed downwardly and outwardly above the course of said first minor currents, and a partition member for distributing a portion of the main water current to each set of said deflector elements. 90

3. A dredging apparatus adapted to be submerged in the path of a water current and comprising two parallel sets of deflector elements arranged one set above the other and each set comprising deflector elements of downwardly curved and slightly twisted outline for producing a plurality of secondary currents directed in a downward and outward direction, and a baffle and partition structure arranged to distribute a portion of the main water current to each set of said deflector elements. 100

4. A dredging apparatus adapted to be submerged in the path of a water current and comprising a row of deflector blades arranged at an angle to the current for splitting the same up into a plurality of secondary currents, said blades having a downwardly curved and twisted contour adapted to deflect said secondary currents downward and also outward in a lateral direction with reference to the course of the main water current, and a second row of downwardly curved and twisted deflector blades arranged to intercept said main current at a higher level than said first blades for producing a plurality of secondary currents directed 110 120 125 130

downwardly and outwardly in paths contiguous to the paths of said first secondary current for augmenting the outward carrying effect thereof.

5. A dredging apparatus adapted to be submerged in the path of a water current and comprising a double row of deflector elements arranged one above the other and each made up of downwardly curved and 10 twisted deflector blades adapted to produce a plurality of secondary currents directed in a downward and outward direction, and a partition member arranged to divide the main water current and direct a portion 15 thereof to each of said rows of deflector blades.

6. A dredging apparatus adapted to be submerged in the path of a water current and comprising a double row of deflector elements arranged one above the other and each made up of downwardly curved and 20 twisted deflector blades adapted to produce a plurality of secondary currents directed in a downward and outward direction, a 25 baffle member for stemming the main water current immediately in front of said deflector blades, and a partition member arranged to divide the main water current and direct a portion thereof to each of said rows 30 of deflector blades.

7. A dredging apparatus adapted to be submerged in the path of a water current and comprising a double row of deflector elements arranged at an angle to the current 35 with one row above the other and each made up of downwardly curved and twisted deflector blades adapted to produce a plurality of secondary currents directed in a downward and outward direction, a baffle 40 member for stemming the main water current immediately in front of said deflector blades, and a partition member arranged to divide the main water current and direct a portion thereof to each of said rows of 45 blades, said partition member extending slightly short of the front portion of said baffle member and the rear portion of the latter having a discharge opening opposite the ends of said upper deflector blades.

50. 8. An apparatus of the character described comprising a forward baffle member, a horizontal partition member having a downwardly inclined front marginal portion, and a double row of deflector blades 55 carried by said inclined marginal portion of the partition member on the upper and lower faces thereof, respectively, and being of downwardly curved and twisted contour adapted to produce a plurality of secondary 60 currents directed in a downward and outward direction, said baffle member having a discharge opening part way along that portion thereof lying opposite the ends of said upper row of blades.

65. 9. A dredging apparatus adapted to be

submerged in the path of a water current and comprising two converging sets of deflector blades, each set comprising a double row of deflector blades arranged one above the other and at an angle to the main water 70 current and being of downwardly curved and twisted contour adapted to produce a plurality of secondary currents directed in a downward and outward direction, and a water-deflecting member arranged to direct 75 a portion of the main water current to each row or said deflector blades.

10. A dredging apparatus adapted to be submerged in the path of a water current and comprising two converging sets of deflector blades, each set comprising a double 80 row of deflector blades arranged one above the other and at an angle to the main water current and being of downwardly curved and 85 twisted contour adapted to produce a plurality of secondary currents directed in a downward and outward direction, baffle means for stemming the main water current immediately in front of said sets of deflector blades, and a water-deflecting member arranged to direct a portion of said main water current to each row of said blades.

11. A dredging apparatus adapted to be submerged in the path of a water current and comprising two converging sets of deflector blades, each set comprising a double row of deflector blades arranged one above the other and at an angle to the main water current and being of downwardly curved and 95 twisted contour adapted to produce a plurality of secondary currents directed in a downward and outward direction, baffle means for stemming the main water current immediately in front of said sets of deflector blades, and a water-deflecting member arranged to direct a portion of said main water current to each row of said blades, said baffle and distributing means cooperating with the forward deflector blades to produce a combined digging action by all the currents discharged therefrom and to deflect the currents discharged from the remainder of the upper deflector blades in outward directions above the paths of the currents discharged from the lower deflector blades.

110. 12. A dredging apparatus adapted to be submerged in the path of a water current and comprising a double row of deflector blades arranged one above the other and all of downwardly curved and twisted contour adapted to produce a plurality of secondary currents directed in a downward and outward direction, and a horizontal partition member arranged to distribute a portion of the main water current to each of said rows of deflector blades, said partition member being formed with vent openings to relieve water pressure in shifting said member into and out of operative position.

125. 13. A dredging apparatus adapted to be

- submerged in the path of a water current and comprising a pair of dredging units each composed of a double row of deflector blades arranged one above the other and at 5 an angle to the water current and the blades of each row being of downwardly curved and twisted contour adapted to produce a plurality of secondary currents directed in a downward and outward direction, said units 10 being assembled with said rows of blades in forwardly converging relation, and a water-deflecting member arranged to direct a portion of the main water current to each of said rows of blades.
- 13 14. A dredging apparatus adapted to be submerged in the path of a water current and comprising a pair of dredging units relatively movable in a vertical direction and each composed of a double row of deflector blades arranged one above the other and at an angle to the water current and the blades of each row being of downwardly curved and twisted contour adapted to produce a plurality of secondary currents directed in a downward and outward direction, said units being assembled with said rows of blades in forwardly converging relation, and interengaging means carried by adjoining sides of said units and adapted 25 to guide the latter in their relative vertical movement.
15. In combination with a catamaran raft

having twin hulls, a dredging unit attached to the prow of each of said hulls, said dredging units being provided with double rows of deflector blades extending in forwardly converging relation, the blades of each row being of downwardly curved and twisted outline adapted to produce a plurality of secondary currents directed in a downward and outward direction, and means operable from the deck of said raft for independently adjusting said dredging units and also for raising and lowering the same into and out of operative position.

16. In combination with a boat, a dredging apparatus connected to the prow of said boat and comprising double rows of deflector blades extending in forwardly converging relation, the blades of each row being of downwardly curved and twisted outline adapted to produce a plurality of secondary currents directed in a downward and outward direction, an auxiliary hull attached to the side of said boat, and a dredging unit connected to said auxiliary hull at the rear of said prow and comprising a double row of deflector blades extending at an angle to the water current and adapted to produce a plurality of secondary currents directed in a downward and outward direction.

In witness whereof I hereunto affix my signature.

LEWIS H. FALLEY.
